J. Battley,

Wind Wheel,

№ 14,997,

Patented June 3, 1856.

UNITED STATES PATENT OFFICE.

JESSE BATTEY, OF HONEOYE FALLS, NEW YORK.

IMPROVED METHOD OF REGULATING WINDMILLS.

Specification forming part of Letters Patent No. 14,997, dated June 3, 1856.

To all whom it may concern:

Be it known that I, JESSE BATTEY, of Honeoye Falls, in the county of Monroe and State of New York, have invented a new and useful Self-Regulating Windmill for Driving Different Kinds of Machinery; and I do hereby declare that the following is a full, clear, and exact description of the construction and operation of the same, reference being had to the annexed drawings, making a part of this specification, in which—

Figure 1 is a perspective view of the principal part. Fig. 2 is a side view of the pressure-regulator E, showing the bar u and weight v; Fig. 3, a transverse section of the vane C, &c., showing the double lever U and its attachment to the vane C, &c.; and Fig. 4 a piece of the segment O and rim m, turned round to show the attachment of the click h and spring x.

I construct my wind-wheel, consisting of wings A and shaft P, upon the top of the building or other frame where it is to be used, the main shaft P extending into the building or frame below for support, and for the purpose of transmitting motion to the machinery by means of bevel-gearing or otherwise, and extending above the wings A a sufficient height to hang the vane C upon. I then construct a frame consisting of the rims m and j, of sufficient size to clear the outer edge the wings A, braced by a sufficient number of arms i, and secured at a proper distance from each other to clear the wings A, above and below, by means of a sufficient number of posts k. This frame is kept in place by the main shaft P passing through the arms in the center above and below the wings A. I attach a sufficient number of rollers or wheels z to the lower rim j to support the frame in a proper manner. The rollers z roll upon the track T when the frame is rotated by the wind or otherwise. I make the track T of either wood or iron, at the option of the builder.

I cover half of the frame with any suitable material above and below and around the outside, making a tight covering, forming the shield B, the object of which is to shield a portion of the wheel from the action of the wind and leaving the other to the action of same when I wish to operate the mill, or

shield the whole when I wish it to stand still. I place the angular wing S on the side of the shield B at point g for the purpose of throwing more wind upon the wings A, and causing it to strike them to better advantage at that point. I arrange the frame and shield so that it will perfectly balance in the wind without the vane C, (having the pressure-regulator E attached,) by attaching one or more wings e to the rims m and j, setting them in such position that they will throw more wind upon the wings A, and at the same time counteract the pressure of the wind against the shield B, &c., and the wing d at point Y to counteract wing S at point g when the vane is at point N. I make my vane sufficiently large to keep the shield in its proper position to the wind, turning it readily with any variation of the wind. It is hung upon the main shaft P, supported by a collar or collars on the same and resting upon the pinion V, running upon the segment O, except in very large mills, where the vane would be too heavy to rest upon the pinion, in which case it rests upon a roller or rollers running upon the track l. I leave an opening in the end of the vane C next the shaft P to receive the regulator D. This regulator is fixed to the vane C and operated by the main shaft P by means of pulleys Q and R, connected by the belt S, which is crossed, giving the regulator the reverse motion of the main shaft P.

The regulator D is a common water regulator or meter.

q and p are small bevel-pinions meshing into the wheel o and playing loose upon the shaft G, being kept in place by collars. The wheel o turns the shaft M and pinion V. The sliding collar r has a slide attached to it extending down nearly to the pinion p, playing in a slot in the shaft G, having a pin attached to the lower end and one near the under side of the pinion q. When the velocity is at the desired point, these pins play clear of the pinions p and q; but when the velocity is too high the extension of the balls n raises the upper pin into a slot in pinion q, causing it to drive the wheel o and pinion V, bringing point N nearer the vane C and shutting off a portion of the wind, and when the velocity is too low the lower-pin drops into a slot in the pinion p, turning the pinion V in the oppo-

site direction and bringing point Y nearer the vane, letting more wind strike the wings A, increasing the velocity, thereby securing uniformity of velocity to the main wheel. When the vane C is at point N, it throws point f to the wind, completely shielding the whole wheel from the action of the wind. When point Y is at the vane, it throws point g to the wind, shielding one half of the wheel and leaving the other to the full action of the wind. Any variation between these points varies the power of the wheel.

The pressure-regulator E is made by attaching an upright wing a to a horizontal shaft H, with bearings resting in boxes b and c. On the side next the wind, when the mill is running, I attach a bar u, with a weight v, varying in size in proportion to the pressure desired to be sustained by the wings A, as shown in Fig. 2. I place a rest y under the bar u to keep it in proper position. I set it at any convenient point on top of the shield or frame, with the plane of the wing parallel with the line from f to N. I attach a cord to the shaft H, pass it over the pulley I directly over the center of the main shaft P and then down to the lever K, which has a slot in the end working on the collar L, which is attached to the slide connected to collar r. The object of this pressure-regulator E is to operate instantaneously on the regulator D in case of sudden gusts of wind, causing it to shut off a portion of the wind before the increased velocity of the main wheel would cause it to do so. Any sudden gust of wind which would increase the velocity beyond the desired point throws back the wing a, raising the lever K by means of the cord F winding upon the shaft II.

In order to stop and start the mill without going out of the building, I attach a double lever U to the lower part of the vane C, the lower ends of which slide upon the track l, and erect a post R at a sufficient distance and of sufficient height to clear the vane C, &c., and then take a rope or cord T of sufficient

length, place the middle of it around a pulley at a convenient point in the building, pass the ends over pulleys X, from there over pulleys or through loop-holes in the arm J directly over the main shaft P, and then pass one end around each of the pulleys W at points N and Y, through loop-holes w, and fasten them to the ends of the double lever U, as shown in Fig. 3. When I wish to start the mill, I draw upon the cord which passes around the pulley at point Y, bringing point Y nearer the vane, and the opposite when I wish to stop it, bringing point N to the vane. Drawing upon the cord T brings the arm of the double lever U up to the vane C, raising the pinion V and lets it slide clear of the segment O.

h is a click with the point kept in place by spring x, as shown in Fig. 4. When the pinion V approaches to point Y, this click drops from the pinion and leaves it stationary at that point; but when the velocity reverses the motion it acts as a tooth, throwing the pinion V back upon the segment O.

I do not claim the wind-wheel in itself considered; neither do I claim the regulator D separately, as similar ones have been used before.

I claim—

1. The regulator E, either with a perpendicular or inclined wing or with the shaft H standing upright and the wing turning horizontally, and its combination with the regulator D, also the rotary vane C and its arrangement, and the connection of the combined regulators E and D, or either of them separately, therewith, for the purpose of securing uniformity of speed in any manner, substantially the same as described.

2. The entire arrangement for starting and stopping the mill, as herein specified, or any arrangement substantially the same.

JESSE BATTEY.
